UNITED STATES PATENT OFFICE

VERNE E. MINICH, OF SCARSDALE, NEW YORK, ASSIGNOR TO THE AMERICAN FOUNDRY EQUIPMENT COMPANY, OF NEW YORK, N. Y., A CORPORATION OF DELAWARE

SAND-TREATING MACHINE

Application filed April 6, 1928. Serial No. 267,949.

This invention relates to sand treating apparatus, and more particularly, to a machine for cutting, screening and piling abrasive material to prepare the same for use in foundries. The machine is adapted to be moved over the foundry floor and to cut or disintegrate the sand or other loose material which may be on said floor. A new and improved type of screen is employed for separating the fine particles from the coarser substances against which the material is propelled after being cut by the machine. If the machine is constantly moved in a forward direction a peaked, elongated pile of sand will be formed, from which workmen may remove the material for subsequent operations.

The cutting, screening and piling machine is preferably of the self-propelled type, mounted upon a chassis having suitable running wheels. An operator may control the movement of the machine over the floor of the foundry by means of suitably arranged control levers for the purpose of reconditioning sand which has previously been used in molds and leaving the same in proper condition for use in carrying on further foundry operations.

This invention further relates to an adjustable screen and cutting cylinder attached to a machine of the above character, and adapted to be selectively adjusted at the will of the operator into either operative or in-operative position. Both the screen and cutting blade are independently mounted for pivotal movement, and may be hoisted by a reel or other suitable means. The screen is formed in a plurality of sections which are adapted to separately act upon the sand and prevent it from clogging at the lower portion thereof.

The invention further comprises an inclined shroud which is attached to the screen and adapted to direct abrasive material upwardly onto the screen and an upper horizontal baffle carried by the screen frame for preventing material from being thrown over the top of the screen by the cutting knives.

An improved vibrating mechanism is also provided for imparting a shaking movement

to the screen for facilitating the separation of the coarse and fine particles. The vibrating mechanism is so designed that the shaking force is dependent upon the weight of the screen.

This application is a continuation in part of my co-pending applications Serial No. 141,711, filed October 15, 1926 for sand cutting, screening and piling machine and Serial No. 181,340 filed April 6, 1927 for sand treating machine.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which—

Fig. 1 is a side elevation of a cutting, screening and piling machine constructed in accordance with this invention;

Fig. 2 is an elevation of the screening mechanism in raised position;

Fig. 3 is a detail view of the bottom portion of the screen showing the arrangement of the various parts;

Fig. 4 is a sectional detail view of a portion of the screen showing the driving mechanism and the piling shroud taken on the line 4—4 of Figure 5;

Fig. 5 is a sectional side elevation of the operating cam, screen and piling shroud;

Fig. 6 is a section taken on the line 6—6 of Fig. 5; and

Fig. 7 is a plan view of the horizontal shroud showing the details of construction thereof.

Like reference characters denote like parts in the several figures of the drawings.

In the following description and in the claims parts will be identified by specific names for convenience, but they are intended

to be as generic in their application to similar parts as the art will permit.

Referring to the drawings more in detail, the invention is shown as applied to a machine of the above character, comprising a suitable framework or chassis 10, which is mounted upon running wheels 11 to enable the same to be moved back and forth over a foundry floor. A suitable source of power such as a motor 12 may be mounted upon the framework 10, and supplied with power by suitable means (not shown).

The motor may be operatively connected to the driving mechanism for impelling the machine, and also to the series of reels to be hereinafter described, which may be utilized in raising and lowering the piling screen and the cutting blades. Various control levers 13 may be arranged in readily accessible positions to enable the operator to guide and control the machine.

The particular source of power and controls employed form no part of the present invention, and consequently will not be described in detail. Any suitable type of mechanism, such as is well known in the foundry art, may be employed for this purpose.

A cutting cylinder 20 provided with a series of cutting blades (not shown) may be pivotally mounted at the rear of the frame, in such manner that it may contact with the floor and the loose material thereon, such as sand when in operative position or may be raised into inoperative position when the machine is to be moved from place to place. Suitable mechanism and connecting means may be provided for driving the cutting cylinder 20, said means preferably being under the control of the operator, whereby they may be connected or disconnected at will. The particular type of connecting means, however, forms no part of the present invention, but is well known in the art and consequently will not be described in detail.

A piling screen 30 may be mounted at the rear of the cutting cylinder 20, and normally positioned in the line of projection of the material treated by said cylinder. The screen may, however, be pivotally mounted and raised by means of a suitable hoist into in-operative position whereby the free passage of the material being treated is not interfered with, and the same may be allowed to form a pile or row in back of the machine.

Attached to the frame 10 may be a series of vertical and horizontal members to provide suitable supporting means for the above mentioned cutting cylinder and piling screen, and for the various controls for operating the same.

Cylinder 20 may be journalled for movement in a suitable bearing 21 carried upon radial bar 22, said bar being journalled for pivotal movement in bearing 23 which is at-

tached to the frame of the machine in any suitable manner. Radial member 22 is extended as by arm 24 at the end of which a hoisting cable or chain 25 is attached. Cable 25 may be connected to reeling mechanism 26, which is carried by the frame of the machine and operated by the prime mover carried thereby. Suitable control mechanism may be included for connecting and disconnecting reel 26 from the source of power whereby, when the same is connected, cable 25 will be reeled up, causing pivotal movement of bar 22 and cylinder 20 connected thereto about bearing 23 into the position shown in Fig. 2. Hand wheel 27 may also be provided for controlling cable 25 if desired.

Piling screen 30 is mounted upon radial arm 31 which is pivotally attached to frame 10 by a suitable bearing 32. Rod 33 pivotally connects the upper portion of screen 30 with bearing 28 carried by frame 10 preferably below bearing 32, and may provide for slight pivotal movement of said screen when the same is vibrated, as hereinafter described.

Screen 30 is secured to a frame work formed of side members 36 which are pivotally secured to rod 33 as by pin 37. Side members 36 and screen 30, which is attached thereto, are formed of a plurality of steps or horizontal sections against which the sand rests, whereby it is prevented from clogging the lower portions of the screen. Members 36 are provided at their base with a horizontal extension 38 (Figure 5) by means of which horizontal screen 39 is supported.

Screen 39 is inclined from the edges of screen 30 to the center portion thereof and is provided at its extreme portions with screenings pans 40 (Figure 4) which direct the coarse material or screenings to the side of the machine. Screen 39 is also provided with an upturned lip 41 on the forward portion thereof which prevents the screenings from passing over the edge of the screen and being again picked up by the cutting blades.

Extensions 38 of frame members 36 are pivotally supported by rod 42 as at pivot point 43, a suitable projection 44 being secured to said members for this purpose.

Rods 42 are pivotally supported at radial arms 31 at a point intermediate of their length. Rods 42 are extended past pivot point 43 and are secured to angle member 45 (Figures 5 and 6) which extends across the entire machine. Sleeves 46 are secured to said angle member 45 and are provided with elongated openings 47 to permit longitudinal movement with respect to rod 48. Bumper block 49 is secured between sleeves 46 and is adapted to contact with rotating cam 50 for shaking the screen.

Cam 50 carried by rod 48 which is supported in suitable bearing 51 located in members 52 (Figure 4) which are secured to radial arms 31. Rod 48 is rotated by bevel gears 130.

53 and 54 (Fig. 1) and associated rotating rod 55. Gears 54 are mounted at the pivot point of arm 31 whereby they are capable of operating irrespective of the angular position of said arm and of screen 30. Suitable driving means (not shown) may be utilized for imparting movement to gears 54 and operatively connecting said gears to motor 12.

10 Members 52 are adapted to prevent abrasive material, picked up by the cutting blades, from being moved laterally and also support angle members 56 which extend transversely of the machine and carry an inclined shroud 57 for directing the material upwardly upon the screen. Member 52 also serves as a support for the screen when the same is in its lower or operative position.

15 The horizontal baffle 58 (Figs. 1 and 7) is secured between radial arms 31 as by crossed members 59. Baffle 58 is provided with an inclined rearwardly extending projection 60 for directing abrasive material upon the screen. Strengthening members 61 may be employed, if desired, for increasing rigidity 20 of the assembly.

25 The screen assembly may be raised to inoperative position by means of cable 62 which may be connected to radial arm 31 and passed over pulley 64 onto reeling drum 63. Reeling drum 63 may be operated by motor or by any suitable means under the control of the operator. When power is applied to reeling drum 63, the entire screen assembly will be rotated about bearings 32 and 28 into the 30 position shown in Fig. 2. Due to the location of pivot point 28 the top of screen 30 is depressed from the position which it would otherwise assume should the assembly be pivoted as a rigid unit about pivot point 32. 40 The total height of the machine is thus reduced.

45 If the cutting cylinder is operated with the screen in raised position the sand may be thrown directly onto a pile, or if the cutting cylinder should also be raised to inoperative position the machine may be freely moved without disturbing loose material over which it may pass.

50 In the operation of the above described machine for the purpose of cutting and screening sand, both cutting cylinder 20 and screen 30 may be placed in lowered position, as shown in Figs. 1 and 5, and the machine moved over the surface to be cleaned or acted 55 upon while power is applied to the cutting blades. Rotation of these blades will then act upon the loose sand or other similar material, cutting the same and dividing it into small particles, in which condition it may be 60 propelled by said blades against screen 30.

65 The fine material will then pass through screen 30 and be deposited upon the floor of the foundry, whereas the coarse particles will be retained, fall into the lower portion of the screen, and be deposited at the side.

by dust pans 40. As shaft 55 is rotated, a vibrating movement will be imparted to the screen by means of cam 50 and bumper block 49 cooperating therewith. The screen suspension is such that the weight of the screen causes the bumper block to exert pressure 70 against cam 50. The pressure is consequently dependent upon the amount of material supported by the screen, whereby a greater mass of material causes a greater shaking 75 movement to be imparted. The steps or horizontal sections of the screen prevent the material from immediately falling to the lower portion thereof and enable the entire surface of the screen to aid in separating so the coarse and fine particles.

Should it be desired to merely cut the sand and to purify the same by aeration without screening, the screen may be raised by means of hoisting drum 63 to the position shown 85 in Fig. 2, while the cutting cylinder 20 may remain in operative position. When the machine is thus passed over the floor, the cutting blades will pick up the sand, and after agitating the particles will throw them 90 through the air into a pile or row at the rear of the machine, the extent of the pile depending upon the quantity of material picked up and the rate of movement of the machine.

95 The machine may be freely moved without treating the material by raising both cutting cylinder 20 and screen 30 to the position shown in Fig. 2, whereby they are entirely removed from contact with the floor and prevented from acting upon material 100 carried thereby.

This invention provides a simple and practical method of selectively and quickly raising either the cutting cylinder or the piling screen into inoperative position without the 105 employment of expensive mounting or complicated mechanism. The reeling drums for the screen and cylinder may be readily operated by the driving motor of the machine, and the controls therefor placed in accessible positions whereby they may be instantly available to the operator.

110 In the drawings accompanying and forming part of this specification, a practical commercial embodiment of the invention is shown, but such illustrations is primarily for purposes of disclosure, and it will be understood that the structure may be modified in various respects without departure from the broad spirit and scope of the invention 115 as hereinafter defined and claimed.

120 What is claimed is:

1. In a machine of the class described, a movable frame, a screen, means for mounting said screen comprising a radial member 125 attached to said screen and pivotally connected to said frame, and means for causing pivotal movement of said radial member whereby said screen may be moved from operative to in-operative position.

2. In a machine of the class described, a moveable frame, a screen pivotally connected thereto, and means for causing pivotal movement of said screen comprising a hoisting cable and a drum for reeling said cable and moving said screen from operative to in-operative position.
3. In a machine of the class described, a frame, mounted for movement over a floor, a screen adapted to be moved from operative to in-operative position, means for mounting said screen comprising a radial member attached thereto and pivotally connected to said frame, a hoisting cable for controlling the position of said screen attached to said radial member and connected to a reeling drum, and means for directing material against the surface thereof.
4. In a machine of the class described, a screen for separating small particles of material from large particles, means for attaching said screen to said machine comprising a radial member, means for loosely connecting said screen to said member, a shroud for directing material against said screen, and a member carried by said radial member and extending below said piling shroud to support the screen for movement over a floor.
5. In a machine of the class described, a screen for separating small particles of material from large particles, means for attaching said screen to said machine comprising a radial member, means for loosely connecting said screen to said radial member, a shroud for directing material against said screen, and means for raising said screen comprising a hoisting cable and a reeling drum cooperating therewith.
6. In a sand cutting, screening and piling machine, a screen support mounted on said machine, a screen mounted on said support, said support comprising upwardly projecting members at each side of the machine, and an inclined plate positioned in advance of said screen to guide sand onto said screen.
7. In a sand cutting, screening and piling machine, a screen support mounted on said machine, a screen mounted on said support, said support comprising upwardly projecting members at each side of the machine, said screen having an inverted V shape and provided with portions inclined toward said frame members, an inclined plate secured to said upwardly projecting members and positioned in advance of said screen to guide sand onto said screen.
8. In a sand cutting, screening and piling machine, a screen, a frame for supporting said screen, a pair of supporting arms pivoted at opposite ends to corresponding sides of the machine and frame, and means for raising said supporting arms to elevate said frame and screen into non-operative position.
9. In a sand cutting, screening and piling machine, a frame mounted on said machine, a screen mounted on said frame, upwardly projecting members on each side of the machine, and an inclined plate positioned in advance of said screen to guide sand onto said screen.
10. In a machine of the class described, a movable frame and a screen pivotally supported thereby, said screen comprising a plurality of substantially vertical sections and substantially horizontal sections located therebetween for impeding the fall of material whereby said material is acted upon by the various parts of the screen and prevented from sliding to the lower portion thereof.
11. In a machine of the class described, a movable frame and a screen pivotally supported thereby, said screen comprising a plurality of substantially vertical sections and a plurality of substantially horizontal sections therebetween whereby material is acted upon by the various parts of the screen and prevented from sliding to the lower portion thereof, and means associated with said machine for imparting vibrations to said screen.
12. In a machine of the class described, a movable frame and a screen pivotally supported thereby, said screen comprising a plurality of substantially vertical sections and a plurality of substantially horizontal sections therebetween whereby material is acted upon by the various parts of the screen and prevented from sliding to the lower portion thereof, and means associated with said machine for imparting vibrations to said screen, said means comprising a rotatable cam, and a bumper block carried by said screen and contacting with said cam.
13. In a machine of the class described, a movable frame and a screen pivotally supported thereby, said screen comprising a plurality of substantially vertical sections and a plurality of substantially horizontal sections therebetween whereby material is acted upon by the various parts of the screen and prevented from sliding to the lower portion thereof, and means associated with said machine for imparting vibrations to said screen, said means comprising a rotatable cam, and a bumper block carried by said screen and contacting with said cam, said screen being so positioned that the weight thereof causes said bumper block to exert pressure against said cam.
14. In a machine of the class described, a frame and a screen supported thereby, said supporting means comprising a pair of radial arms pivotally secured to said screen and a second pair of radial arms pivotally secured to said frame and said screen, the pivot point of said second pair on said frame being below the corresponding point for said first pair, whereby the upper portion of said

- screen is depressed when said screen is elevated by pivotal movement.
15. In a sand cutting machine, a screen pivotally mounted thereon, means for raising said screen to inoperative position and means for depressing the top of said screen to reduce the over-all height of said machine.
16. In a sand cutting machine, a screen pivoted thereto, radial arms pivoted to said machine and secured to the upper and lower portions of said screen respectively, the relation of said arms being such that the upper portion of said screen is depressed when raised into inoperative position.
17. In a sand cutting machine, a stepped screen comprising horizontal and vertical sections, an inverted V shaped horizontal screen at the lower portion of said screen, and screening pans associated with said V shaped screen for depositing screenings laterally of said machine.
18. In a sand cutting machine, a stepped screen comprising horizontal and vertical sections, an inverted V shaped horizontal screen at the lower portion of said screen, and dust pans associated with said V shaped screen for depositing screenings laterally of said machine, the forward end of said V section being provided with an upwardly extending lip to prevent material passing thereover.
19. In a sand cutting machine, a movable screen pivoted thereto having a stepped surface, a V shaped horizontal screen at the lower portion thereof and an inclined shroud associated with said V shaped section for directing material thereon.
20. In a sand cutting machine, a screen pivotally mounted thereon, and a horizontal baffle plate carried by said machine for preventing material from passing over said screen.
21. In a sand cutting machine, a screen, radial members for pivotally mounting said screen to said machine, and a horizontal baffle secured to said members for directing material against said screen.
22. In a sand cutting machine, a screen, radial members for pivotally mounting said screen to said machine, and a horizontal baffle secured to said members for directing material against said screen, said baffle being provided with a rearwardly extending inclined portion for directing material to the upper portion of said screen.
23. In a sand cutting machine, a screen mounted thereon, an inclined shroud for directing material from said floor onto said screen, and a horizontal baffle for preventing material from passing over said screen.
24. In a sand cutting machine, a stepped screen, a frame therefor, means for pivotally supporting the upper portion of said frame to said machine, radial arms pivoted to said machine, means for pivoting the lower por-
- tion of said screen to said radial arms, a vibrating cam supported between said radial arms, means associated with said screen for cooperating with said cam, means including bevel gears for operating said cam irrespective of the position of said radial arms, a shroud supported by the lower portion of said arms for directing material onto said screen, and a baffle supported by the upper portion of said arms for preventing material from passing over said screen.
